UNITED STATES PATENT OFFICE.

HENRY J. ROTH, OF NEW YORK, N. Y., ASSIGNOR TO EBERHARD FABER PENCIL COMPANY, OF BROOKLYN, NEW YORK, A CORPORATION OF NEW YORK.

PENHOLDER.

1,079,516.

Specification of Letters Patent.

Patented Nov. 25, 1913.

Application filed September 7, 1912. Serial No. 719,055.

To all whom it may concern:

Be it known that I, HENRY J. ROTH, a citizen of the United States, residing in the borough of Brooklyn, county of Kings, 5 city and State of New York, have invented certain new and useful Improvements in Penholders, of which the following is a specification.

This invention is directed to the provision 10 of an improved form of penholder of the type in which a grip is provided at the end of the holder so constructed that it can be moved inwardly a small amount toward the axis of the holder in response to the pressure 15 of the fingers thereon. Penholders of this character can be more readily held in the hand in the desired position and can be used with less of a tiring effect upon the hand.

20 In accordance with the invention, a sleeve or tube is provided upon the end of the holder made of such material as cork which will depress or move inwardly when subjected to pressure by the fingers, and the 25 construction is such that an air space is provided within this sleeve between the ends thereof where the sleeve is supported. In this way, the desirable capacity for depressing 30 in response to pressure is obtained in the grip and the structure may be such that the holders may be manufactured at comparatively low cost. This low cost is due primarily to the fact that the sleeve or tube of cork or similar material may be of uniform 35 cross-sectional shape throughout, the supports for the tube being of greater diameter at the ends of the sleeve than between those ends where the air space is provided within the sleeve.

40 The preferred embodiment of the invention is illustrated in the accompanying drawings in which—

Figure 1 is an elevation of the pen and holder, Fig. 2 is a longitudinal section of 45 the end of the holder, Fig. 3 is a similar view showing certain of the parts in elevation, and Fig. 4 is a transverse section on line 4—4 of Fig. 2.

50 Referring to these drawings, 5 indicates the shaft of the holder, preferably round and tapering toward one end. At its larger end, it is reduced in size to form a tenon consisting of two cylindrical portions 6 and 7, the portion 7 at the end being of smaller 55 diameter than the portion 6. This provides

a shoulder 8 at the junction of the two portions 6 and 7 and a shoulder 9 at the junction of the portion 6 and the shaft 5. A tube of thin sheet-metal 10 is mounted on the portion 7, that is, the portion 7 projects 60 into one end of tube 10 with the end of the tube abutting against shoulder 8. This tube is of less exterior diameter than the diameter of the cylindrical portion 6. The opposite end of tube 10 receives the usual 65 split metallic thimble 11 for holding the pen between it and tube 10.

On the outer end of tube 10 is a circumferential enlargement 12 of the same exterior diameter as the portion 6 of the 70 tenon on the shaft 5. Preferably, this enlargement 12 is a small metallic tube or ring drawn inwardly at one end so as to bear on tube 10. The other end of the ring 12 bears against a metallic ring or washer 13 75 which fits snugly on tube 10 as shown and is preferably positioned by spreading the extreme end of tube 10 as indicated.

The grip of the holder is shown at 14. It is in the form of a tube or sleeve of uniform cross-section throughout and is made of cork or a similar material which will give when subjected to pressure. At one end, this sleeve fits upon and is supported by the portion 6 of the shaft, its end abutting against the shoulder 9. Its opposite end fits upon and is supported by the enlargement or ring 12, the extreme end abutting against washer 13. As both the ring 12 and the cylindrical portion 6 are of 80 larger diameter than the exterior diameter of tube 10, a space is provided between sleeve 14 and tube 10 between the ends of the sleeve, as is shown in Figs. 2, 3 and 4. By reason of the provision of this air space 85 within the grip, the sleeve 14 will give and be depressed when the holder is gripped in the hand, the walls of the sleeve moving more or less into the inclosed space within it, dependent upon the pressure. By this 90 construction, the holder is made much more convenient to use, much more so than when the material constituting the grip lies directly against the shaft or a part mounted thereon. Furthermore, this construction 100 permits of manufacturing the holders at low cost. It will be noted that the tube or sleeve 14 of cork is of uniform cross-section from end to end. This form of sleeve 105 may be used because of the provision of 110

supporting surfaces coacting with the ends of the sleeve which surfaces are of larger diameter than the portion of the structure lying between them.

5. If desired, a metallic ferrule 15 may be provided at the upper end of sleeve 14. This ferrule is a thin metal tube and is inserted in the end of sleeve 14 before assembling the latter on the holder so that 10 the flange at its end will abut against shoulder 9.

Having described my invention, what I claim as new therein and desire to secure by Letters Patent of the United States is:

15. A penholder comprising a shaft reduced in size at one end thereof to provide two shoulders and cylindrical portions of different diameters, adjacent thereto a tube of thin sheet-metal of less exterior diameter than the larger of said cylindrical portions and into one end of which the smaller 20 of said portions projects to support the

tube on the shaft, a pen-holding clip at the opposite end of said tube, a circumferential enlargement on said tube adjacent to said opposite end and a tubular grip of cylindrical form presenting an unbroken cylindrical surface and of substantially uniform cross-section throughout, said grip inclosing said tube and mounted at one end upon the 25 larger of said cylindrical portions abutting the shoulder at the end thereof and at the other end upon said circumferential enlargement, said grip being spaced apart from said tube and being made of such material that it may be depressed more or less into the space between it and the tube, substantially as set forth.

This specification signed and witnessed this fourth day of September, 1912.

HENRY J. ROTH.

Correction in Letters Patent No. 1,079,516.

It is hereby certified that in Letters Patent No. 1,079,516, granted November 25, 1913, upon the application of Henry J. Roth, of New York, N. Y., for an improvement in "Penholders," an error appears in the printed specification requiring correction as follows: Page 2, line 18, after the word "diameters" strike out the comma and same page and line, after the word "thereto," insert a comma; and that the said Letters Patent should be read with this correction therein that the same may conform to the record of the case in the Patent Office.

Signed and sealed this 16th day of December, A. D., 1913.

[SEAL.]

J. T. NEWTON,

Acting Commissioner of Patents.
